UNITED STATES PATENT OFFICE.

WILLIAM C. CODMAN, OF PROVIDENCE, RHODE ISLAND, ASSIGNOR TO THE GORHAM MANUFACTURING COMPANY, OF SAME PLACE.

DESIGN FOR A HANDLE FOR SPOONS, &c.

SPECIFICATION forming part of Design No. 25,504, dated May 19, 1896.

Application filed April 1, 1896. Serial No. 585,827. Term of patent 7 years.

To all whom it may concern:

Be it known that I, WILLIAM C. CODMAN, of the city of Providence, in the county of Providence and State of Rhode Island, have invented and produced a new and original Design for Handles of Spoons, Forks, and Similar Articles; and I hereby declare that the following is a full, clear, and exact description of the same, reference being had to the accompanying drawings, forming part of this specification.

Figure 1 is a view of the front or obverse side of the handle. Fig. 2 is a view of the reverse side of the handle.

The leading feature of my design consists in the peculiar and novel outline of the handle and in the ornamentation of the same.

In the drawings, A indicates the lower end of the handle; B, the neck of the handle; C, the plate, and D the upper end of the handle. In outline the handle has, at its junction with the bowl of a spoon or the body of a fork, the spreading base 3, the handle proper commencing at the bead 4. The neck B is very short, its narrowest part at 5 being located at about one-eighth the length of the handle, and the length of the neck about one-fifth of the length of the handle. From the point 5 the width of the handle increases gradually to the upper end 6 in a line so slightly curved that it practically follows the straight broken line 7 on Fig. 2, curving slightly inward above the point 8 and turning abruptly inward at the upper end, terminating in a slightly-raised

pyramidal end, presenting to the eye the 35 appearance of a long tapering plate of the handle terminating in a short neck with the graceful curved outline of Greek simplicity. The ornamentation of the obverse and the reverse sides of the handle consist in the raised 40 rounded marginal beads 10, terminating at the upper end of the handle in the scrolls 11 and the radially-extending pyramidal Greek ornament 9. On the reverse side the junction of the handle with the article to which 45 it is attached is ornamented with the conventional Greek ornament used in the Ionic and other orders and known as the "honeysuckle" ornament. In addition to the ornamentation common to the two sides of the handle the obverse or front is ornamented by the two rows 50 of beads commencing at the scrolls 11 and gradually diminishing in diameter. To the eye the handle, in outline and ornamentation, presents the severe graceful appearance of 55 Greek designs.

Having thus described my newly-designed handle, I claim as new and desire to secure by Letters Patent—

The design for the handle of spoons, forks 60 and similar articles, herein shown and described.

In witness whereof I have hereunto set my hand.

WILLIAM C. CODMAN.
